UNITED STATES PATENT OFFICE.

FRANCOIS N. SAVARD, OF AVON, MASSACHUSETTS.

DEVICE FOR SOFTENING SHOES.

Application filed September 15, 1922. Serial No. 588,437.

To all whom it may concern:

Be it known that I, FRANCOIS N. SAVARD, a citizen of the United States, residing at Avon, in the county of Norfolk and State of Massachusetts, have invented new and useful Improvements in Devices for Softening Shoes, of which the following is a specification.

This invention relates to a device for softening portions of shoes, particularly box toes and has for its object to provide a heater through the medium of which the toe portions of shoes and particularly the box toe or stiffener for the toe cap may be heated, and thereby softened preparatory to undergoing the lasting operation.

In the manufacture of shoes at the present time it is customary to utilize artificially prepared sheet materials as substitutes for leather to stiffen and reinforce certain portions of the shoe, particularly the toe cap and in order to properly last the shoe at the toe portion where it is necessary to wipe the various materials comprising the toe cap, toe box and lining over the bottom of the last it becomes necessary to soften said materials, particularly the toe box, to render them pliable in order that said toe box, together with the toe cap, will not break or crack while being subjected to the unavoidable strains incident to the lasting operation.

I am aware of numerous devices for softening shoes by subjecting the same directly to the influence of hot vapor such as steam, but devices of this character tend to discolor and otherwise injure certain classes of leather, especially those employed in the construction of tan colored shoes and certain other light colored leathers used in women's shoes. Devices employing electric heat have also been used but the heat produced by these devices is extremely dry and the danger of injuring the leather by burning and also from removing too much of the natural moisture contained in the leather is too great to render these devices practical.

It has been demonstrated that whereas live steam in direct contact with the leather is often injurious, that nevertheless as a heating medium however, it is the most satisfactory, and it is, therefore, an object of this invention to provide a heating device constructed in such a manner that live steam may be indirectly employed as the heating medium, the induced heat radiating from the device being so confined that portions of

shoes may be easily subjected to and influenced by a quality of heat which at the same time is neither too dry or too moist and various portions of said shoes are thereby rendered sufficiently pliable to be easily lasted without danger of being injured.

The invention consists in the combination and arrangement of parts set forth in the following specification and particularly pointed out in the claims thereof.

Referring to the drawings:

Figure 1 represents a front elevation of a device for softening shoes embodying the invention.

Fig. 2 is a transverse section taken on the line 2-2 of Fig. 1.

Like numerals refer to like parts throughout the several views of the drawings.

In the drawings, 5 represents a casing constituting a heating unit and embodying therein a central body member 6 at the opposite ends of which are plates 7 and 8. The casing 5 is constructed in the form of an inverted U and the interior thereof constitutes a chamber for the reception of a heating medium, preferably live steam, which is admitted through a pipe 10 at one end of said casing. The passage of steam through the pipe 10 into the chamber 9 is controlled by a valve 11. Discharge orifices 12 and 13 are provided at the end of the casing 5 opposite the entrance pipe 10, and discharge pipes 14 and 15 communicate therewith for the purpose of carrying off the steam or the condensation therefrom. A valve 16 is provided for the pipe 15.

The formation of the casing 5 is such as to provide a recess 17 in the under side thereof between downwardly projecting portions 18 of said casing, and the plates 7 and 8 not only close the opposite ends of the chamber 9, but the opposite ends of the recess 17 as well. The recess 17 is of sufficient size and form to receive the toe portions of a plurality of shoes 19 as illustrated in Fig. 2, the latter being in the process of construction, each shoe being located upon a last 20. The casing 5 is mounted upon a suitable frame 21 embodying therein legs 22 and is tipped at a slight angle upon said frame to facilitate the insertion and removal of the shoes to and from the recess 17.

Means are provided for supporting the shoes 19 while being heated and for adjusting the height of the supporting means as follows: Mounted upon the frame 21 be-

neath the casing 5 is a shelf 23, the upper surface of which is provided with longitudinally extending strips 24 forming corrugations provided for the purpose of preventing the shoe from slipping upon said shelf and also for providing a means for positioning the heel portion of said shoe thereon. The shelf 23 is preferably inclined at a slight angle to a horizontal plane and rests upon angular 5 supporting members 25 which are adjustable vertically upon the legs 22, and said members are held in position upon said legs by bolts 26 which pass through slots 27 provided in said legs. The inclination of the shelf 23 10 moreover may be changed if desired, by adjusting the height of the forward and rear supporting members 25 relatively to each other. All sizes of shoes may, therefore, be supported upon the shelf 23 beneath the casing 5 and treated within the passage 17 and the distance to which said shoes may project within said recess is determined by the position of the heel portion of said shoe upon the shelf 23 and the height of said shelf upon 15 the frame 21. Tie rods 28 and 29 are provided to reinforce the legs 22 on the frame 21.

The general operation of the device is as follows:—In preparing the shoes for lasting 20 after the upper of the shoe 19 has been pulled over the last 20 and it is ready to be operated upon by the lasting machine, the shoe is placed upon the shelf 23 with the toe portion thereof projecting into the recess 17 of 25 the casing 5, there being sufficient space provided for a plurality of said shoes to be placed upon said shelf and rest thereon side by side. The shelf 23 is located in an inclined position, the inclination of which may 30 be changed as desired by adjusting the angular supporting members 25, and the height of said shelf relatively to the casing 5 may also be adjusted in a similar manner. The strips or corrugations 24 provided upon the 35 upper surface of the shelf 23 are utilized to position the heel portion of the shoes upon said shelf and also to prevent said shoes from slipping thereon, and the distance to which the toe portion of the shoes may project into 40 the recess 17 is determined by the position of the heel portion of the shoe upon the shelf 23. Steam admitted to the chamber 9 heats 45 the walls of the casing 5, and the radiated heat which is confined within the recess 17 50 because of the position and form of said recess acts upon the toe portion of the shoe and particularly upon the toe box thereof, and after the toe portion of the shoe has been 55 within the recess a sufficient length of time 60 for said toe box to be rendered pliable, said shoe is withdrawn and subjected to the lasting operation without danger of injuring the toe portion of the shoe.

It has been found while performing the 65 lasting operation upon shoes that have been

treated by the device hereinbefore described that it is not necessary to hurry the lasting operation in order to complete the same before the toe box cools, as shoes treated without employing heated moisture remain pliable longer because the material does not cool as quickly, and therefore the operative is given plenty of time to properly perform the lasting operation. 70

I claim:

1. A device of the character described comprising, in combination, a U-shaped heating unit provided with a U-shaped chamber for a heating medium located within the interior thereof and a recess in the side thereof and means to support a shoe with a portion thereof projecting into said recess. 75

2. A device of the character described comprising, in combination, a U-shaped heating unit provided with a U-shaped chamber for a heating medium located within the interior thereof and a recess in the side thereof, and means to support a shoe with a portion thereof projecting into said recess, said shoe support being adjustably mounted so as to vary the distance between the same and said heating unit. 80

3. A device of the character described comprising, in combination, a heating unit provided with a chamber for a heating medium located within the interior thereof and a recess in the side thereof, and a support for a shoe located adjacent to said heating unit, said shoe support being adjustably mounted so as to vary the distance between the same and said heating unit and also to incline said support at an angle to a horizontal plane. 85

4. A device of the character described comprising, in combination, a heating unit provided with a chamber for a heating medium located within the interior thereof and a recess in the side thereof, means to support a shoe with a portion thereof projecting into said recess, said shoe support being adjustably mounted so as to vary the distance between the same and said heating unit and means whereby the heel portion of said shoe may be positioned and prevented from slipping longitudinally thereof upon said support. 100

5. A device of the character described comprising, in combination, a heating unit provided with a chamber for a heating medium located within the interior thereof and a recess in the side thereof, a support for a shoe located adjacent to said heating unit, and adjustably mounted so as to vary the distance between said support and said heating unit and also to incline said support at an angle to a horizontal plane and means whereby the heel portion of said shoe may be positioned and prevented from slipping longitudinally thereof upon said support. 105

6. A device of the character described comprising, in combination, a heating unit provided with a chamber for a heating medium located within the interior thereof and 5 a recess in the side thereof, and a support for a shoe located adjacent to said heating unit and adjustably mounted so as to vary the distance between said support and said heating unit and also to incline said support at an angle to a horizontal plane, said support being provided with a corrugated upper surface to prevent a shoe from slipping thereon.

7. A device of the character described 15 comprising, in combination, a U-shaped casing provided with a recess in a side thereof and having a U-shaped steam chamber located within the interior thereof, means to conduct steam to said chamber, said steam within said 20 chamber being segregated from said recess and means to support a shoe with a portion thereof projecting into said recess.

8. A device of the character described 25 comprising, in combination, a casing provided with a recess in the underside thereof and having a steam chamber located within the interior thereof, means to conduct steam to said chamber, said steam within said

chamber being segregated from said recess, and a support for a shoe located beneath 30 said casing and adjustably mounted so as to vary the distance between said support and said casing and also to incline said support at an angle to a horizontal plane.

9. A device of the character described 35 comprising, in combination, a casing provided with a recess in the underside thereof, and having a steam chamber located within the interior thereof, means to conduct steam to said chamber, said steam within said 40 chamber being segregated from said recess and a support for a shoe located beneath said casing and adjustably mounted so as to vary the distance between said support and said casing and also to incline said support at 45 an angle to a horizontal plane, said support being provided with a corrugated upper surface to prevent a shoe from slipping thereon.

In testimony whereof I have hereunto set my hand in presence of two subscribing 50 witnesses.

FRANCOIS N. SAVARD.
